DESIGN FOR A FOUNTAIN PEN

Martin Ullman, New York, N. Y., assignor to
M. J. Waldinger, New York, N. Y.

Application April 14, 1945, Serial No. 118,997

Term of patent 14 years

(CL D74—17)

To all whom it may concern:

Be it known that I, Martin Ullman, a citizen of the United States, residing at New York city, in the county of New York and State of New York, have invented a new, original, and ornamental Design for a Fountain Pen, of which the following is a specification, reference being had to the accompanying drawing, forming part thereof.

In the drawing

Fig. 1 is an elevational view of a fountain pen, showing my new design;

Fig. 2 is an elevational view of the cap of the pen; and

Fig. 3 is an elevational view of the barrel of the pen.

The essential features of the design reside in the parts shown in full lines.

I claim:

The ornamental design for a fountain pen, substantially as shown and described.

MARTIN ULLMAN.
